UNITED STATES PATENT OFFICE.

LEWIS E. WATERMAN, OF ROCKFORD, ILLINOIS, ASSIGNOR TO EMERSON MANUFACTURING COMPANY, OF ROCKFORD, ILLINOIS, A CORPORATION OF ILLINOIS.

SEEDING-MACHINE.

No. 848,790.

Specification of Letters Patent.

Patented April 2, 1907.

Application filed February 19, 1907. Serial No. 358,210.

To all whom it may concern:

Be it known that I, LEWIS E. WATERMAN, a citizen of the United States, residing at Rockford, in the county of Winnebago and State of Illinois, have invented certain new and useful Improvements in Seeding-Machines, of which the following is a specification.

The object of this invention is to construct a seeding-machine on the general principles as shown in my Patent No. 844,429, granted February 19, 1907.

The difference between this application and my patent above referred to rests in the employment of a hand-lever for adjusting the shovel-supporting frame in its connection with the plow-support and in the manner of holding the shovel-supporting frame from lateral movement, which will not interfere with the vertical movements thereof.

In the accompanying drawings, Figures 1 and 2 are perspective views of my improved seeding-machine as seen from opposite sides.

The main frame comprises the axle 1, supporting-wheels 2, frame 3, supported by the axle, tongue 4, connected to the frame 3, seeding mechanism 5, supported by the frame and driven through the axle, and a seat 6, supported at the rear end of the frame.

30 A support or sleeve 7 is connected with the frame 3 in any suitable manner. A plow support or standard 8 is slidably mounted in the sleeve 7 to move vertically therein. To the lower end of the standard 8 is connected

35 a plow 9.

A toothed segment 10 is fixedly connected to the upper end of the standard 8, and a hand-lever 11 is pivotally supported by the standard and provided with the usual dog engagement with the toothed segment 10.

40 An arm 12 extends laterally from the hand-lever 11, and a link 13 connects the arm with the upper end of the standard. By means of this toothed segment and hand-lever the standard can be raised and lowered and held in its adjusted position.

45 To the lower portion of the standard is pivotally connected a frame 14, supporting covering-shovels 15.

50 To the upper portion of the standard is fixedly connected a toothed segment 16, and a hand-lever 17 has a pivotal connection with the standard and is provided with the usual dog for engagement with the toothed segment.

55

A projection 18 extends laterally from the hand-lever, to the free end of which is connected a rod 19. The lower end of the rod is pivotally connected with the shovel-supporting frame.

60

By means of the hand-lever 17 and its connection with the shovel-supporting frame the shovel can be adjusted vertically and held when adjusted so that by operating the hand-lever 11 the plow and covering-shovels 65 will be raised and lowered in unison.

An extension 20 is connected to the seat-support 21 and depends between the side bars of the covering-shovel-supporting frame.

To the side bars of the covering-shovel-supporting frame is pivoted a cross-bar 22, to the center of which is connected a rod 23, which passes through an eye 24, extending from the extension 20. From the rear face of the cross-bar 22 extend two arms 25, one 75 located each side of the extension 20 and closely fitting against it.

As the arm extension 20 is rigid with the frame 3 and the arms 25 embrace it on either side, a connection is formed between the 80 shovel-supporting frame and the frame 3, which will hold the shovel-supporting frame from lateral movement. The eye 24 guides the rod 23 and permits of a vertical movement of the rod through it. This connection, in conjunction with the cross-bar 22, 85 serves to hold the two side bars of the shovel-supporting frame in a horizontal plane, so that there will be no twisting action.

I claim as my invention—

90

1. In a seeding-machine the combination of a main frame, a plow-standard capable of a vertical movement in connection with the frame, a plow supported by the standard, means for raising and lowering the standard 95 and holding it in its adjusted position, a covering-shovel-supporting frame pivotally connected with the standard, a toothed segment connected with the standard, a hand-lever for the toothed segment, and a connection 100 between the hand-lever and covering-shovel-supporting frame.

2. In a seeding-machine, the combination of a main frame, a covering-shovel-supporting frame capable of a vertical movement, a 105 bar depending from the main frame, a cross-bar connecting the side bars of the shovel-supporting frame, two arms extending from the cross-bar and receiving the bar between them, thereby forming a guide for the shovel- 110

supporting frame in its vertical movements and preventing lateral movement of the shovel-supporting frame.

3. In a seeding-machine, the combination of a main frame, a covering-shovel-supporting frame capable of a vertical movement, a cross-bar connecting the side bars of the shovel-supporting frame, a rod connected to

the cross-bar, and a guide for the upper end of the rod permitting the rod to move vertically.

LEWIS E. WATERMAN.
